UNITED STATES PATENT OFFICE.

ELIAS L. ELLIOTT, OF NEW YORK, N. Y.

MULTIPLE SOCKET FOR INCANDESCENT LAMPS.

No. 853,231.

Specification of Letters Patent.

Patented May 14, 1907.

Application filed May 18, 1906. Serial No. 317,509.

To all whom it may concern:

Be it known that I, ELIAS L. ELLIOTT, a citizen of the United States, residing at New York, in the county of New York and State of New York, have invented certain new and useful Improvements in Multiple Sockets for Incandescent Lamps, of which the following is a specification.

This invention relates to that class of holders for incandescent electric lamps commonly known in the trade as "wireless clusters," and involves novel methods of construction by means of which certain electrical and mechanical advantages are obtained.

The method of construction is clearly described in the following specification, reference being had to the accompanying drawings in which like letters refer to like parts.

My device consists of a multiple holder or socket for receiving a number of incandescent electric lamps, and is so constructed that by a single connection of the leading-in wires to the binding posts, electrical connection is made to each of the lamps when inserted in the socket.

It consists essentially of two main parts, namely: a base by which it is attached to the supporting fixture, and which contains one contact piece, or set of contact pieces, for making connection with the lamp, and a body, which directly supports the lamps and contains the other contact piece, or set of contact pieces for completing the electric circuit.

In the accompanying drawings, Figure 1 is a cross section through the multiple holder in a plane vertical to its normal position; Fig. 2, is a plan view of the base from below, the body portion being removed; and Fig. 3 is a top plan view of the body portion showing the interior.

The base 1, is constructed of insulating material, preferably porcelain, having a flange or projection 2, adapted to receive the metallic contact piece 4, and provided with a central aperture 16, to receive the supply wires 6, 7.

I have shown the contact piece 4, in the form of an inverted truncated cone stamped up from a single sheet of metal, although it may be made in any convenient shape. It is provided with a central opening 5, for one of the leads 6, and is secured to the base by means of the bolt 15, which also constitutes the binding post by which the lead 6 is con-

nected thereto. Encircling the flange 2, is a metal collar having a depending threaded portion 11 and a flat horizontal portion 17, secured by means of bolts 14, to the base, one of the bolts 14, serving as a binding post to connect the collar with the lead 7, the latter passing through a channel 13, in the flange 2 of the base.

The body 3, is preferably constructed of porcelain, or other insulating material, and is provided with openings 8, to receive the threaded thimbles or shells 9, which constitute sockets for the reception of the lamp bases. Extending around the inner circumference of the body is a metal ring 10, with which the shells or sockets 9, make electrical connection. The shells may be fastened to the ring in some substantial manner, as by riveting or soldering, thus securing the ring 75 rigidly to the body. It is evident, however, that the ring may be secured to the body in some other manner, and merely contact with the sockets.

As a means of attaching the body portion 80 to the base, I preferably thread the ring 10, to correspond with the threads on the collar 11, so that the parts may be united by simply screwing the body on to the base.

In installing the multiple socket, the base 85 may be attached directly to a wooden support by screws 12, passing through holes provided for this purpose. In case it is desired to fasten the socket to a metal support, these screws can engage a metal cover having the necessary means of attachment. One of the leading-in wires 7, is then brought through the channel 13, in the flange and attached to the binding post 14, in connection with the collar 11. The other lead 6, is now passed 95 through the hole 5, in the bottom of the contact piece 4, and clamped by the nut on the bolt 15, which at the same time fastens the contact piece to the base. The body is then screwed on to the base, the threaded ring and collar holding the parts securely together. The lamps may now be screwed into the sockets until their inner contacts engage the contact piece 4. In the present case I have shown the multiple socket arranged to connect the lamps in parallel, the inner lamp contacts connecting with the central contact piece 4, and the outer or threaded contacts connecting with the collar 11 through the ring 10; but I may divide the contact pieces 100 into segments for the purpose of connecting the lamps in series, and I desire it to be un-

derstood that I intend to include this arrangement within the scope of my claims, the specific construction being covered in a separate application.

5 It is evident that any convenient number of lamps may be used simultaneously in my multiple socket, and that they may be arranged at any angle below the horizontal, depending only upon the number and position 10 of the sockets provided in the body.

I claim:

1. A multiple socket for incandescent electric lamps comprising an insulating base carrying a contact piece for making electrical connection with each lamp, and an insulating body detachably secured to the base and arranged to support the lamps in position and carrying a metallic contact piece for completing the electrical circuit with each lamp; 20 substantially as described.

2. A multiple socket for incandescent electric lamps comprising an insulating base carrying a contact piece for making electrical connection with each lamp, and an insulating body provided with a plurality of lamp-holding devices, said devices carrying means for detachably securing the base and body together; substantially as described.

3. A multiple socket for incandescent electric lamps comprising an insulating base carrying a contact piece for making electrical connection with each lamp, and an insulating body provided with a plurality of lamp-holding devices, said devices carrying means for detachably securing the base and body together, and for completing the electrical circuit with each lamp; substantially as described.

4. A multiple socket for incandescent electric lamps comprising an insulating base provided with contacts for connection with the supply leads, an insulating body arranged to support the lamp in position, and means detachably securing the base and body together, said means bringing the lamps into electrical connection with the supply leads; substantially as described.

5. A multiple socket for incandescent electric lamps comprising an insulating base provided with contacts for connection with the supply leads, and an insulating body arranged to support the lamps in position, and provided with means for detachably securing the base and body together and for completing the electrical circuit with each lamp; substantially as described.

6. A multiple socket for incandescent electric lamps comprising an insulating base provided with contacts for connection with sup-

ply leads, and an insulating body carrying 6c lamp-holding devices and means for simultaneously securing the base and body together and connecting said devices with one of said leads; substantially as described.

7. A multiple holder for electric lamps 65 comprising an insulating base portion provided with means for connecting with supply wires, and an insulating body portion constituting a casing for said holder and adapted to support and insulate a plurality of lamp-receiving shells; substantially as described.

8. A multiple holder for electric lamps comprising an insulating base portion provided with means for connecting with supply wires, and an insulating body portion adapted 75 to support and insulate a plurality of lamp-receiving shells, and means for electrically connecting said shells with one of the supply wires when the parts are assembled; substantially as described.

9. A multiple holder for incandescent lamps comprising an insulating base, a metallic contact piece for connection to one of the supply wires, an insulating body containing metallic shells or thimbles for receiving 85 the lamp bases, said thimbles forming part of the electric circuit, and means for attaching the body to the base and connecting each lamp with the supply wires; substantially as described.

10. In a multiple holder for electric lamps, the combination of an insulating base, a metallic contact piece attached thereto forming one part of the electric circuit, a flanged collar having a depending screw threaded portion 95 and forming a part of the electric circuit, an insulating body having openings, threaded shells adapted to receive the lamp bases in said openings, and a threaded ring secured to said body, electrically connected with said shells and adapted to engage said threaded collar; substantially as described.

11. In a multiple holder for electric lamps, the combination of an insulating base provided with a central depending flange, a metallic contact piece secured to said flange, a depending threaded metallic collar secured to the base, an insulating body having openings for lamp sockets, and a threaded ring secured to said body and arranged to connect 105 with the sockets and to engage said threaded collar; substantially as described.

In testimony whereof I affix my signature in presence of two witnesses.

ELIAS L. ELLIOTT.
